UNITED STATES PATENT OFFICE.

CHARLES M. HANNIS, OF HUDSON, MASSACHUSETTS, ASSIGNOR OF ONE-HALF TO
BARNETT MATROSS, OF BOSTON, MASSACHUSETTS.

LIFE-PRESERVER.

1,063,256.

Specification of Letters Patent. Patented June 3, 1913.

Application filed July 24, 1912. Serial No. 711,301.

To all whom it may concern:

Be it known that I, CHARLES M. HANNIS, a citizen of the United States, residing at Hudson, in the county of Middlesex and 5 State of Massachusetts, have invented a new and useful Life-Preserver, of which the following is a specification.

This invention relates to an improvement in life preservers.

10 The primary object of the invention is to provide a life preserver which will completely cover the body of the wearer, excluding water, means being provided for admitting air to the wearer.

15 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

20 In the drawings:—Figure 1 is a front elevation. Fig. 2 is a side elevation, the portion of the garment which incases the head, being shown in section. Fig. 3 is a view, showing the head covering portion in detail. 25 Fig. 4 is a detail view of the closure. Fig. 5 is a sectional view of the upper portion of the garment.

In the drawings, 10 designates a garment which is formed of rubber or any other suitable 30 flexible water-excluding fabric, the garment being formed with legs 11 and arms 12, the body portion 14 terminating in the head covering 15 which is enlarged to allow for the air space 16, the garment adjacent 35 its upper terminal being provided with openings 17 which receive the frames 18 for glasses 19. The garment is formed below said glasses with an opening 20 through which extends an air tube 21 which is formed 40 of flexible material, a collar 22 being formed on said tube and secured to the garment. The portion 24 of said tube which is disposed 45 exteriorly of the garment, is curved downwardly, air being admitted through the opening in said tube. The portion 25 of the tube

is maintained against collapsing by the metallic sleeve 26 which extends within the tube, the portion 25 of the tube being arranged to extend within the mouth of the wearer, the opening in said tube being closed 55 by the tongue of the wearer while beneath the surface of the water.

The body of the wearer is admitted through the open end of the garment, there being ankle straps 26 which clamp the garment to 60 the limbs of the wearer. A cord 27 is secured to the garment by the chain 28, the open end of the garment being brought together and folded as shown in Fig. 4, and the cap 29 then being placed over the same 65 and the cord wound about said cap thus forming a water tight closure for the opening in the garment. The chain 28 is connected to the hook 28', the same being detached from said hook when it is desired to 70 remove the cord from the folded end of the garment. A strap 30 is secured interiorly of the garment, adjacent the opening in the same, said strap being arranged to embrace the head of the wearer, to space the portion 75 15 from the head, and provide the air space. The garment is designed to protect the body of the wearer from exposure, the construction of the garment being such that the wearer may either swim or float, air being 80 admitted through the tube 21. It will be noted that when the head of the wearer is out of the water he may remove his tongue from the end of the tube and receive air.

The many advantages of a construction of 85 this character will be clearly apparent as it will be noted that the same provides a garment being of such construction that the wearer may either swim or float as desired, and while incased in the garment air 90 is admitted to the same. It will be noted that the entire construction is such as may be easily and economically manufactured.

What is claimed is:—

A garment, comprising a body portion, 95 said garment being provided with an open end, a cap for said open end, said garment being provided with an opening, a tube formed with a collar which is secured to the garment, the portion of said tube which is 10

disposed exteriorly being curved downwardly, a metallic sleeve disposed in the portion of said tube which is arranged interiorly of the garment, and means arranged to embrace the head of the wearer to provide an air space.

In testimony that I claim the foregoing

as my own, I have hereto affixed my signature in the presence of two witnesses.

CHARLES M. HANNIS.
